DESIGN FOR A TUCKED FABRIC

Benjamin Beidner, New York, N. Y.

Application June 1, 1939, Serial No. 85,295

Term of patent 3½ years

To all whom it may concern:

Be it known that I, Benjamin Beidner, a citizen of the United States of America, residing in New York city, in the Borough of Manhattan, county and State of New York, have invented a new, original, and ornamental Design for a Tucked Fabric, of which the following is a specification, reference being had to the accompanying drawing, forming part thereof, wherein

The design is characterized by a series of solid and broken tucks alternately arranged over the surface of the fabric, each group of broken tucks being arranged in upper and lower paths, having a skip, stop appearance as shown.

I claim:

The ornamental design for a tucked fabric, substantially as shown and described.

BENJAMIN BEIDNER.
